CLAIM

The ornamental design for a storage box as shown and described.

DESCRIPTION

1.1 is a top, front, left side perspective view of a storage box showing the new design;

1.2 is a front view thereof;

1.3 is a right side view thereof;

1.4 is a left side view thereof; and

1.5 is a top view thereof.

Lightly shaded portions of the storage box in reproductions **1.1-1.5** are for the purpose of illustrating portions of the storage box that form no part of the claimed design.

1 Claim, 5 Drawing Sheets
